FIG. 1.

FIG. 2.

FIG. 3.

FIG. 4.

FIGURE 1 is a top perspective view from the front of a combined memo board and adjustable utility tray showing my new design;

FIGURE 2 is a top plan view of the article as shown in FIG. 1;

FIGURE 3 is a front elevation view thereof;

FIGURE 4 is a bottom plan view of said article;

FIGURE 5 is a rear elevational view of said article;

FIGURE 6 is a side elevational view of said article as seen from the opposite side as that shown in FIGURE 1;

FIGURE 7 is a perspective view shown on a reduced scale depicting the article of FIGURES 1-6 with the tray in an adjustably lowered position;

FIGURE 8 is a rear elevational view of the article depicted in FIGURE 7, shown on substantially the same reduced scale as FIGURE 7; and

FIGURE 9 is an enlarged side elevational view similar

to FIGURE 6 but showing the article of FIGURES 7 and 8, and as seen from the opposite side as that shown in FIGURE 7.

The dominant features of my design reside in those portions shown in full lines.

I claim:

The ornamental design for a combined memo board and adjustable utility tray, substantially as shown and described.
